Attorney.

UNITED STATES PATENT OFFICE.

CHARLES T. DRAPER, OF CLEVELAND, OHIO, ASSIGNOR TO THE DRAPER MANUFACTURING COMPANY, OF CLEVELAND, OHIO, A CORPORATION OF OHIO.

REINFORCED METALLIC CHIME SEAM AND METHOD OF PRODUCING SAME.

Application filed February 24, 1920. Serial No. 360,883.

To all whom it may concern:

Be it known that I, CHARLES T. DRAPER, a citizen of the United States of America, residing at Cleveland, in the county of Cuyahoga and State of Ohio, have invented certain new and useful Improvements in Reinforced Metallic Chime Seams and Methods of Producing Same, of which the following is a specification.

10 My invention relates to improvements in reinforced metallic chime seam and method of producing same. The object thereof is the fabrication of a cheaper, stronger and more durable seam for large metallic containers, such as sheet metal barrels, than has previously appeared in the art.

There are shown in Letters Patent No. 891,895 to Young and No. 1,125,011 to Draper types of chime seams employing specially rolled angle iron sections as the protective member or armor, and in all prior metallic barrels with which I am acquainted such special forms have been employed. As a matter of fact, the chime constructions 25 therein shown in said patents are idealized and do not accurately represent the commercial article, for the reason that close conformity of the seam and armor is not obtainable in practice throughout the periphery and profile of the angular section.

These angular sections may not commonly be obtained in the market of uniform thickness and proportions, while the cutting and shaping of such sections is attendant with 35 certain technical difficulty in effecting a complete weld and common deformation and departure from a true circle of the precise dimensions desired.

Accordingly, I have devised ways and means for fabricating from commercial band iron, which averages of better grade and greater uniformity than angle iron, a closely conforming chime ring or armor for the head seams of metallic barrels. This, however, necessitates the overcoming of technical difficulties in shaping the armor member from material which of necessity must be of relatively heavy gauge. However, the welding of a plain band iron hoop and the removal of the resulting burr or projection are much more readily effected than where angle iron shapes are similarly fabricated.

The armor member preferably is slightly

flared along one edge between suitable rolls, is then curled to form an overlapping flange 55 and recess for the seam, while the hoop is brought to accurate shape and dimensions, and is thus shaped to fit within the head of the barrel or container between suitable dies, and finally the inserted chime seam and 60 its armor are rolled into continuously conforming surfaces throughout the body of the completed chime, whereby adequate reinforcement is insured. Numerous and exacting tests of containers embodying my improvements have demonstrated that the type 65 of armor or reinforcing member herein disclosed maintains the chime seam effectively intact under conditions which will produce damage and leakage in similar chime 70 seams armored by the well known angle iron members. The seam and armor of my improvement are found to become deformed and bend together as a unit, instead of separating under extreme stress, as will be 75 found to occur now and again with the older types of reinforced chimes. This advantage doubtless springs from the close conformity 80 of the chime seam and its chime ring or armor throughout, whereas the original profile of angle iron may not thus be brought to exact conformity by known commercial methods, while the size of the chime ring fabricated therefrom and its shape are not 85 accurate and exact. Thus, the chime seam proper is not interiorly stayed and supported uniformly throughout the circumference thereof, and bending strains, in consequence, are more liable to impair the seam and result in leakage.

Considered from a manufacturing standpoint, the armor or chime ring produced from band iron may be brought to exact dimensions and shape between massive dies, and with less expense than is involved in 95 practicing the older art. The encircling portion of the hoop preferably is so shaped that the seam snugly fits thereunder and the final conforming rolls very easily produce the closely conforming unit of seam and armor 100 with a minimum expenditure of labor and power and without deformation. This operation is analogous to the final closure of the seam.

Further explanation of my improved 105 method and structure, and the advantages

thereof may best be made in connection with the accompanying drawings, wherein:—

Fig. 1 is a fragmentary elevation centrally broken away, of the straight strip or band from which the hoop is made.

Fig. 2 is a perspective view of the strip shown in Fig. 1 after it has been rolled to an annular shape.

Fig. 3 is a perspective view of the hoop shown in Fig. 2 after its ends have been butt welded.

Fig. 4 is a sectional view of the hoop after being trued and flared between suitable dies.

Fig. 5 is a sectional view of the hoop shaped to receive the chime seam.

Fig. 6 is a sectional view of the hoop shown in Fig. 5 in position on the chime of the container.

Fig. 7 is a sectional view of the hoop and chime of Fig. 6; said hoop having been finally rolled to complete the armored chime.

Figs. 8 and 9 are enlarged cross sectional fragmentary views of the seam and hoop corresponding to Figs. 6 and 7 respectively.

Fig. 10 is a similar enlarged cross sectional view of a hoop or chime ring formed of angle iron, applied to the seam of the container.

Fig. 11 is an enlarged fragmentary view in section illustrating the initial truing and flaring of the hoop between coacting rolls.

Fig. 12 is an enlarged fragmentary view also in section wherein the hoop is shown between the coacting dies just as the curling and sizing of the hoop is beginning, and Fig. 13 is a similar view illustrating these members at the completion of the operation.

Fig. 14 is an enlarged fragmentary view showing in cross section the rolls for completing the armored chime seam, with the container positioned therein.

Throughout the several figures of said drawings I have employed the same character of reference to indicate similar parts.

By referring to the earlier figures of the drawings my improved method will be very readily grasped, while upon comparing Figs. 9 and 10, an important advantage of the resulting reenforced chime seam may be made quite apparent. The latter figure may be taken as typical of reenforced chime seams of the art, wherein various angular shapes are employed for the reinforcing member. Therein the lack of conformity between the seam and its armor is graphically suggested, but a transverse section would emphasize this disadvantage, since the shaping of the members is found to be irregular and lacking in uniformity. On the other hand, Fig. 9 illustrates in cross section an armored chime seam with its members conforming throughout, and which is readily fabricated in accordance with the method about to be explained.

The blank *a* of Fig. 1 is accurately cut of the desired length from rolled band iron which is of uniform thickness throughout. After rolling to hoop shape, as shown in Fig. 2, the ends are butt-welded at *a'* in the well known manner and the burr is smooth or cleaned off. The ends of band iron, obviously will permit of a more accurate and complete weld than do the limbs of an angle iron section when roller into hoop form, for the reason that the ends of the former come squarely together and meet on the welding line.

One edge of the completed hoop is now slightly flared at *a''*, as by rolling between suitable rolls *b*, *c*, shown diagrammatically in section in Fig. 11, which serve as well to true the hoop and prepare it for the dies. The trued hoop is now placed between said dies *d*, *d'*; the former having a curved annular groove *d''* and being of the exact diameter to bring the hoop to the desired size. Fig. 12 illustrates the dies and hoop in fragmentary form at the commencement of their operation and Fig. 13 similarly illustrates them at the conclusion thereof. It will be observed that the flaring edge *a''* has now been overturned to form a curved flange *a'* annularly of the hoop which is adapted readily to fit over the seam *e* of the barrel's chime as shown in Figs. 6 and 8. The hoop also has been brought to size accurately to fit within the recessed head *e'* of the barrel or metallic container.

The final operation consists merely in spinning the flange *a'* closely about and moulded into accurate conformity with the annular seam *e*, as by the coacting rolls *f*, *f'*, shown in Fig. 14. These rolls are adapted to compress the chime with considerable force and bring the parts of the seam and reinforcing chime ring into closely conforming engagement, so that the chime will be practically integral as a whole and the parts will stay each other and bend together under excessive strains or blows. This is possible in using the lighter and accurately shaped chime ring made of band iron in accordance with the method here pointed out.

On the other hand, with the employment of chime rings made as heretofore, of angular sections, such close conformity will not be obtained. First, an angle section does not fit as closely within the barrel head and may not be fabricated as accurately as may my improved chime ring. Second, the angle section, which must be cold rolled or spun, persists somewhat in its original shape at the apex or angle. Third, the flange requires much more power and a greater range of bending, in order to bring it into overlapping relation with respect to the seam.

These features will be more apparent by referring to Fig. 10, wherein the angle section *g* is shown in position upon the seam

e of the container. It will be noted that the apex *g'* does not closely conform for some distance interiorly of the chime, while the leg *g''* must be actuated approximately 5 through 90° in addition to subsequently spinning its edge beneath the seam *e*. This illustration is not by any means exaggerative of actual chime ring fabrication, which, of course, is not capable of the accurate, closely 10 conforming construction obtainable by employing the shaping and sizing dies above described. Moreover, the chime ring formed of angle iron is found under tests approximating severe usage, to exhibit a tendency 15 to open and separate or bend independently of the seam, so that the annular deformation is more likely to result in producing leakage, than results from the employment of my improved chime ring under like conditions. Thus, drums embodying my invention, when dropped from a considerable 20 height to a concrete floor have been found to bend as a unit along a section or sections of the chime, like the bending of a cable or 25 rope and without any tendency to open the seam.

Reverting again to Fig. 10, it will be noted that the vertical leg of the angle iron ring is shown to be of slightly less diameter towards the apex of the angle. This departure 30 from a true cylindrical form insured by my improved chime ring, leaves the rear of the chime seam unsupported and hence liable to open under severe usage. The butt welding 35 of an angle iron ring tends commonly to produce this condition, since in welding the length of the horizontal leg *g''* end to end, a certain compression and distortion adjacent to *g'* is induced and the diameter 40 of the resulting ring is unequally affected. When the ring, however, is expanded or accurately sized by a suitable die, its diameter is uniform throughout.

Having now described the method of my 45 invention and its preferred product or embodiment, I claim as new and desire to secure by Letters Patent, the following:—

1. The herein described method of producing a continuously conforming metallic 50 chime for containers, which consists in fabricating from a flat metallic band, a ring or hoop, welding its ends together, shaping an annular edge approximately of the form of the protected seam, introducing the seam of the container within said annular edge and 55 tightly compressing the hoop about said seam continuously in conformity to its outer and inner periphery, substantially as set forth.

2. The herein described method of producing a closely conforming metallic chime for containers, which consists in fabricating a chime ring from a flat metallic band, welding its ends together, shaping said band approximately to the desired form, sizing the 60 ring between dies accurately to conform to the head of the container, and overturning an edge of the ring to enclose and protect the exterior of an inserted annular seam, substantially as set forth. 70

3. The herein described method of producing an armored chime for metallic containers, which consists in fabricating a chime ring, shaping it approximately to the final form, sizing the ring between dies, inserting the annular seam of the container and the head within the ring, and compressing an edge of said ring about the seam, substantially as set forth. 75

4. The herein described method of fabricating a protected chime seam for metallic containers, which consists in cutting a blank of the required length from an iron strip of even gauge, bending it to circular form, butt welding its ends, shaping one edge 80 within a die to afford an open rimmed conforming annular recess for the chime seam, inserting said seam within the recess, and forcibly closing the protective ring in close 85 engagement exteriorly of the seam, substantially as set forth. 90

5. The herein described method of producing a protected chime seam for metallic containers, which consists in bending and welding an undersized hoop from band iron, 95 flaring an edge thereof, expanding said hoop accurately to the requisite size of said container, shaping the flared edge to afford a conforming annular recess for the chime seam, and overturning said edge about the 100 inserted chime seam of the container, substantially as set forth.

6. The herein described method of fabricating a protected chime seam for metallic containers, which consists in cutting a blank 105 of the required length from an iron strip of even gauge, bending it to circular form, butt welding its ends, rolling one edge thereof slightly to flare the same, overturning the edge between dies whereby a semi-conforming open rimmed receptacle is formed for the chime seam of the container, inserting said seam and closing the protective ring 110 tightly about the seam, substantially as set forth. 115

In testimony whereof I do now affix my signature.

CHARLES T. DRAPER.
